(57) **CLAIM**

The ornamental design for a hand held manipulator for a video inspection device, as shown and described.

DESCRIPTION

FIG. 1 is a perspective view of an exemplary video inspection device which embodies a housing in accordance with the present design;

FIG. 2 is a perspective view of a first embodiment of the housing;

FIG. 3 is a rear view of the first embodiment of the housing;

FIG. 4 is a front view of the first embodiment of the housing;

FIG. 5 is a side view of the first embodiment of the housing, the other side view being a mirror image thereof;

FIG. 6 is a top view of the first embodiment of the housing;

FIG. 7 is a bottom view of the first embodiment of the housing;

FIG. 8 is a perspective view of a second embodiment of an exemplary video inspection device which embodies a housing in accordance with the present design;

FIG. 9 is a perspective view of the second embodiment of the housing;

FIG. 10 is a rear view of the second embodiment of the housing;

FIG. 11 is a front view of the second embodiment of the housing;

FIG. 12 is a side view of the second embodiment of the housing, the other side view being a mirror image thereof;

FIG. 13 is a top view of the second embodiment of the housing; and,

FIG. 14 is a bottom view of the second embodiment of the housing.

It is to be understood that those portions of the housing shown in broken line in the accompanying figures do not constitute an integral part of the claimed design and, therefore, are disclaimed as part of the claimed design.
